UNITED STATES PATENT OFFICE

1,995,101

PAPER MAKING APPARATUS

Percy Andrew Jackson, Holyoke, Mass., assignor
to American Writing Paper Company, Inc.,
Holyoke, Mass., a corporation of Delaware

Application November 18, 1933, Serial No. 698,659

1 Claim. (Cl. 92—43)

This invention relates to improvements in paper-making apparatus and is directed more particularly to improvements in paper machines of the so-called cylinder type.

5 The principal objects of the invention are directed to the provision of improvements in paper-making machines of the cylinder type to facilitate the producing of better and stronger paper. This is accomplished according to this invention by the provision of means to bring about the vibration or shaking of certain parts thereof in order to provide a more thorough intermingling, and more efficient felting, of the paper-making fibers.

In paper-making apparatus of the cylinder type 15 where successive cylinder moulds and their vats are employed a layer of fibers is taken on by the cylinder mould of the first vat and transferred to a felt and other layers, formed on successive cylinder moulds, are successively transferred in superposed relation to build up a web. To bring about the desired felting or intermingling of the fibers it has been attempted to cause the fibers taken on by one cylinder mould to be disposed in a different direction than those taken on by another. To accomplish this the paper-making material is caused to flow straight into and through one vat and in another vat the material is caused to flow in a cross current or more or less obliquely. This is so that the fibers of the 20 different layers are arranged more or less in different directions to provide a web having fibers lying in various directions.

The results referred to however have not been altogether satisfactory and according to the novel 25 features of this invention means is employed to bring about more efficient intermingling of the fibers on each cylinder mould and a better felting in each layer. This is accomplished by vibrating or shaking certain parts of the paper-making apparatus to agitate the paper-making material as it is delivered to the cylinder moulds. Where a plurality of cylinder moulds are used to form a web each constituent layer of the web has its 30 fibers well felted so that altogether it is possible to produce a finished web of paper having great strength. The features of this invention are adapted for broad application so that various 35 papers may be made.

40 The invention will be described in reference to a paper-making apparatus having a plurality of cylinder moulds and vats and in the preferred form thereof it will be described in connection with the accompanying drawing wherein:

50 Fig. 1 is a side elevational view of a paper-mak-

ing apparatus embodying the novel features of the invention, and

Fig. 2 is a sectional elevational view taken on the line 2—2 with parts broken away to show certain details of construction.

5 By reference to the drawing the invention will be described in detail.

Vats are represented at 2 and 2 it being understood that there may be as many of such vats as may be desired arranged side by side.

10 Cylinder moulds 4 may be of usual form and have curved surfaces. For each cylinder there is provided a couch 6 carried in arms 8 movably mounted in some suitable manner as on support 10 on top of which is a rail 12. A lower run of 15 felt is represented at F and as is common practice this contacts the cylinder. The upper run is supported by suitable carrying rolls associated with the rails 12 in the usual manner.

The vat or tank has side walls 16 and 18 and 20 a bottom wall 20. Forward and back end walls are represented at 22. In the form of the vat shown the walls described may be of wood while the end walls 22 may consist of inner wooden wall members 24 and outer plates 26 (see Fig. 2). 25 The outer plates 26 are secured to the end walls in some manner so that altogether the walls are held in proper relation to provide a strong durable vat.

A partition wall 28 extends between the end 30 walls of the vat. A horizontally disposed wall 30 extends from the upper side of the wall 28 towards the cylinder mould.

A curved baffle or plate member 34 extends 35 downwardly from the wall 30 and between the end walls and is more or less concentric with the cylinder. The lower end of the baffle 34 is spaced from and attached to the lower wall by a member 36.

Another curved baffle or plate 40 extends downwardly from the wall 16. Its upper end is secured to the wall 16 while its lower end is secured to and spaced from the bottom wall by a member 42, similar to the part 36.

40 Paper-making material is delivered to the vat 45 by means of a pump or the like through an inlet pipe 46 which leads into the space between the wall 18 and partition 28 and then flows upwardly and over the horizontally disposed part 30 into the space between the cylinder mould 50 and the plates 34 and 40.

The end wall members 24 are provided with outlets of some sort indicated generally by 48. The end plates 26 as shown in Fig. 2 are provided with outwardly extending walls such as 50, 52, 55

54, 56, 58, 60 and 62 connected to vertically disposed outer walls 64 to form one or more compartments which are located at opposite ends of and separate from the vat. A vertically extending wall 66 is provided so as to form in conjunction with the vertical wall 62 an overflow compartment which is separate from another compartment formed by walls 50, 52, 54, 56, 58, 60 and 66 which compartment is in communication with the vat through openings 48.

10 As has been described, the paper-making material, which is usually fibrous material suspended in water, is delivered to the vat through the pipe 46 so that it flows upwardly and over the member 30 into the space between the cylinder mould and members 34 and 40. In ordinary practice, water flows through the mould in such a way that the fibers are deposited thereon and the water then flows outwardly through the ends of 15 the cylinder mould, through openings 48 into the chambers formed on the end plates. The chambers on opposite ends of the vat are connected by a pipe 70 which in turn is connected as shown to a discharge pipe such as 72. Thus water 20 which passes through the cylinder mould for the depositing of fibers is conducted away from the vat by means of the pipes 70 and 72.

25 The ends of the cylinder mould are sealed against the ends of the vat in any suitable way such as by a more or less flexible strip 9 associated with a seal ring 11 carried by the end walls, the strip overlying a circumferential flange, associated with the ends of the cylinder mould, as shown.

30 The chambers between the walls 62 and 66 are overflow chambers and the walls 66 are preferably of such a height or may have some means associated therewith so that a desired height of material is maintained in the vat. When the material overflows into the overflow chambers 35 it may be conducted away therefrom by means of pipes 76.

35 In lieu of the vat described, of course, it may be desirable in some cases to use a vat constructed differently, the form shown being merely for purposes of assisting in the description and disclosure of the invention.

40 As one novel feature of the invention it is desired to agitate, or create such movements in the paper-making material as will bring about an intermingling and felting of the fibers thereof. To that end means is provided to facilitate 45 vibrating the vat and cylinder relative to one another and such means will now be described.

45 The cylinder mould has a shaft 80 which is journalled in bearing standards 82 at the front and rear sides of the vat while stuffing boxes such as 84 are associated with the shaft and the end wall of the vat to permit relative axial 50 movements of the cylinder and vat.

55 Socket members 86 are provided on the under side of the vat and similar members 88 are pro-

vided which may be associated with a plate 90. The sockets 88 and/or the plate 90 associated therewith may be supported by a floor or foundation. The adjacent faces of the members 86 and 88 are provided with curved sockets as shown 5 so that rollers 90' may be disposed therebetween and in that way the vat is so mounted that it may be moved back and forth or vibrated. Any means other than this, such as links connecting the vat to a suitable support, may be employed, it being essential that some means be provided to permit slight relative endwise movements of the vat and of the cylinder.

10 Various means may be employed to bring about vibration of the vat but, for purposes of description, a vibrator indicated generally by V is shown.

15 This vibrator V may consist of a disc 94 having a shaft rotatable in a standard 96 and the shaft may have a pulley 98 associated therewith which is driven from any suitable source of power. The disc is slotted on its outer face as at 100 and a block such as 102 is adjustable transversely to the axis of rotation of the disc by means of bolts 104 engageable with suitable nuts working in the slot 100. A stud 106 is provided 20 on the block 94 and it is connected by means of a connecting rod 108 to a bracket such as 110 provided on the end of the vat. By moving the block 102 the position of stud 106 may be varied relative to the axis of rotation of member 94.

25 Thus as the disc rotates the vat is vibrated slightly to more or less agitate the paper-making material therein and cause the fibers thereof to be thoroughly intermingled so that when they are taken on by the cylinder mould they are disposed at various angles to one another. In that way it is possible to produce a layer for a web of paper which is strong and durable and by employing a plurality of vats and agitating them as described the layers for the web may be properly superimposed with each layer having the fibers thereof well felted or intermingled so that the combined layers form a very novel and superior web of paper.

30 While I have described my invention in great detail and with respect to preferred embodiments thereof, I do not desire to be limited to such detail or embodiments since many changes or modifications may be made without departing from the spirit and scope of the invention in its broader aspects. What I desire to claim as new and secure by Letters Patent of the United States is:

35 The combination in a cylinder paper-making machine of, a support, a vat mounted on said support for movements relative thereto, said vat having side and bottom walls rigidly secured together, bearings rigidly associated with said support, a cylinder mould in said vat having end parts journalled in said bearings, means associated with said vat for bringing about said movements thereof relative to said support.

40 PERCY ANDREW JACKSON.
